DRIVE-IN RESTAURANT BUILDING

John Garry Clay, Roanoke, Va., assignor to Farrows, Inc.,
Roanoke County, Va., a corporation of Virginia

Filed Aug. 31, 1961, Ser. No. 66,566

Term of patent 14 years

(Cl. D13—1)

FIGURE 1 is a top plan view of the drive-in restaurant building embodying my design;

FIGURE 2 is a side view of the drive-in restaurant building embodying my design;

FIGURE 3 is an enlarged detailed view of the left-hand end portion of the drive-in restaurant building shown in FIGURE 2;

FIGURE 4 is an end view of the left end of the drive-in restaurant building shown in FIGURE 2; and

FIGURE 5 is a fragmentary enlarged detailed view of the lower left corner of the trellis portion of FIGURE 3.

The opposite side of the drive-in restaurant building from that shown in FIGURE 2 is substantially identical therewith.

The right end of the drive-in restaurant building shown in FIGURE 2 is identical with the end shown in FIGURE 4 except the decorative trellises projecting sidewardly do not appear.

The drawing is stippled to show contrasting appearance.
I claim:

The ornamental design for a drive-in restaurant building, substantially as shown and described.
